Frederic M. Keeney
ATTORNEY.

UNITED STATES PATENT OFFICE.

JOHN GEORGE McGILPIN, OF EL MONTE, CALIFORNIA.

SIPHON VALVE.

Application filed June 10, 1921. Serial No. 476,486.

To all whom it may concern:

Be it known that I, JOHN GEORGE McGILPIN, a citizen of the United States, residing at El Monte, in the county of Los Angeles and State of California, have invented a new and useful Siphon Valve, of which the following is a specification.

This invention relates to an injector device in which a fluid under pressure is utilized to force a liquid from a lower to a higher level, the device being adaptable as a substitute for a pump, and its objects are, primarily, to provide means for siphoning waste water from basements and excavations, and to eliminate the use of a pump generally required for this purpose.

Other objects are to provide means for controlling the fluid which serves to create the suction for draining such basement or excavation of the accumulating water, to provide means whereby the suction force is quickly established, and thereafter maintained, to provide means for regulating the flow of liquid which is to be pumped or forced to the higher level, and to provide a device of this character which is free from projections which would interfere with the convenient handling of the device in limited spaces.

My invention is a device of the general character noted, that embodies the peculiar and novel construction of parts hereinafter more fully described, specifically pointed out in the appended claims, and illustrated in the drawings. Steam and water under pressure may be considered substantially, as equivalents for generating the motive force for the raising and forcing of liquids.

In the drawings, Figure 1 is a side view of my improved siphon. Fig. 2 is a central longitudinal section of the same. Fig. 3 is a cross-section on line 3—3, of Fig. 2. Fig. 4 is a side view showing the device connected to a hose. Fig. 5 is a detail view of the supporting ring. Fig. 6 is a perspective detail view of the expander for the flexible elements. Fig. 7 is a fragmentary and enlarged detail view showing the jet-spreading elements in expanded position.

Referring to the drawing, the practical arrangement of my invention comprises the casing 11, merging at the outer end 12, in a tapering nozzle 13, exteriorly screw-threaded for attaching a discharge hose 14, which conveys the water or liquid to the desired point of delivery. The casing is extended

to form the projecting inner nozzle 15, in chamber 16, which is provided with inlet suction openings 17, in the outer wall of casing 11, the openings being covered by screens 18, serving to prevent entrance of material which would clog the chamber and nozzle.

An integral diaphragm wall 19, is provided with an orifice 20, opposite opening 21, in inner nozzle 15, and coaxial therewith. A sleeve 22, having screw-threaded connection with casing 11, may be rotated to open and close suction openings 17, and may be adjusted to any desired point, thereby partly closing the apertures in accordance with the pressure of the fluid discharged from orifice 20. At its opposite end, casing 11 is provided with the interiorly threaded extremity 23, into which is screwed the member 24, provided with a central valve seat 25, and at its opposite extremity, with a stuffing box 26. A valve member 27, is provided with an enlarged end 28, interiorly threaded for a hose connection 29, which provides the actuating fluid under pressure. The valve member 27, terminates in a tapered end 30, adapted to engage with valve seat 25, in closed position. The valve member is rotated to seat the end 30 in its valve seat, and thereby shut off the actuating fluid.

When valve 30 is in its fully open position, the actuating fluid is delivered through orifice 20 in a relatively narrow jet. In the fully open position of valve 30, the flexible elements 31, on the end thereof, lie closely together, and thus the steam jet issuing from orifice 20 is discharged in the center of orifice 21. (This may tend to prevent immediate priming of the device.) That the self-priming operation will take place speedily, I have provided flexible elements 31, fixed to the end of valve member 30. A ring 32, retained by packing 33, supports the actuating element 34, for expanding or spreading elements 31. As elements 31 are expanded, and while they do not fully close the orifice 20, the force jet is correspondingly expanded within the delivery nozzle, thereby quickly creating sufficient suction within chamber 16. The expanding element 34 is rotative relative to supporting ring 32, but is retained against longitudinal movement, while elements 31, advance longitudinally upon rotation of valve member 27, and may therefore be adjusted to spread the force jet within the delivery nozzle.

- The entrance to the discharge tube has a certain area for the liquid which is to be pumped, to enter such discharge tube. If the discharge tube area be so large in proportion to the actuating jet, no priming will occur, and if the discharge tube area be relatively very small in proportion to the actuating jet, the capacity of the device for service as a pump, is reduced accordingly. The 5 expanding elements herein described serve to expand the jet at the entrance to the discharge tube to cause immediate suction therein. After the operation has started, the area of the jet is then reduced by adjusting the spreading elements out of the path of the jet, and the resulting increased 10 velocity of the jet serves to move the increased amount of liquid that enters around the jet at the entrance to the discharge tube.
- 10 In an ordinary device not having my jet-spreading elements, on the emission of the jet from the orifice, the same may travel within the discharge tube some distance, before spreading sufficiently therein to cause 15 the suction required for operation as a pump, and, at the point where the jet has filled the discharge tube, its velocity is so reduced, that priming of the device does not readily occur. With my jet-spreading elements 20 serving to expand the jet at the entrance to the discharge tube, the area for the liquid to be pumped is relatively much reduced, and the velocity of the jet is, at this point, approximately at its maximum, thus 25 causing the device to become instantly primed.
- It is to be understood that when the valve 30 is fully closed upon its seat, there will be no jet issuing from orifice 20, but the issuing jet is expanded upon adjustment of the 35 expanding elements 31.
- In use, the device being connected to the fluid pressure supply and with the delivery 40 hose, is then submerged in the liquid which is to be forced to a higher level. If the fluid actuating pressure be very low, then the sleeve is adjusted to reduce the area of 45 the inlet or suction openings. On the other hand, the fluid actuating pressure being high, the sleeve is adjusted to its fully open 50 position. The fluid pressure may be otherwise regulated by turning the adjustable valve. Adjustment may also be made for expansion of the injector jet which passes 55 from the jet orifice into the delivery nozzle. The main casing and controlling nozzle or valve are detachable, and the device may be used without the controlling valve.
- What is claimed is:
- 60 1. In a siphon valve, the combination with a casing enclosing a chamber, and having inlet ports for the chamber, of a tubular inner nozzle extending into the chamber, a diaphragm integral with the casing and having an orifice coaxial with the inner nozzle and spaced apart therefrom, a sleeve 65 screwed to the casing and having a central valve seat, and at its opposite end a stuffing-box, a valve member sliding through said stuffing-box, and cooperating with the valve seat to form a passage closure, and an expandible element connected to the sliding valve member, and extending in the diaphragm orifice. 70
2. A device of the class described comprising a casing having means for connection at one end with water under pressure, and provided with an interiorly arranged cone-shaped wall-diaphragm having a central orifice, an inner nozzle forming a continuation at one end of said casing, and provided with an opening co-axial with the orifice and spaced apart therefrom, said casing embodying a chamber encircling said orifice and inner nozzle, and having water intake ports leading to said chamber, and an expandible valve member protruding in said orifice. 75
3. In a siphon valve, the combination with a casing forming a suction chamber and having inlet ports leading to said chamber, an inner nozzle terminating in said chamber, and a diaphragm having an orifice co-axial with the inner nozzle, of screen elements covering said inlet ports, a sleeve having screw-connection with the casing and adjustable to cover said ports, a sleeve member connected to the casing having a valve seat in advance of the central jet orifice, a valve co-operating with the valve-seat to close the 80 passage to the orifice, and expandible elements fixed to the valve, and extending within the orifice, and operative to increase or decrease the diameter of the jet within the inner nozzle. 85
4. The combination with a casing enclosing a suction chamber, an inner water discharge nozzle concentric with the casing, and ports in the casing leading to the suction chamber, of a diaphragm integral with the casing and having an orifice co-axial with the inner nozzle, spaced apart therefrom, and smaller than the opening in the inner nozzle, of a valve member controlling the passage to the jet-orifice, movable expanding elements fixed to the valve member, and extending within the orifice, and an expandible element rotatively mounted between the expanding elements and fixed against longitudinal movement, said expandible elements extending within the orifice. 90
5. The combination with a casing enclosing a suction chamber and having inlet ports, an inner nozzle, and a diaphragm pierced with a central orifice coaxial with the opening in the inner nozzle, of a valve to control the jet passing through the central orifice, and jet expanding means operated by the movement of the valve, and extending within the orifice. 95

6. The combination with a casing enclosing a suction chamber and having inlet ports, an inner nozzle terminating in an opening within the chamber, and a dia-
5 phragm pierced with a central orifice co-axial with the opening in the nozzle, of a sleeve forming a communicating passage for the inlet of fluid pressure to the orifice, expanding elements extending within the ori-
10 fice, a valve in the sleeve operative on its initial movement to expand said expanding elements in the path of the jet, and operative on further movement to close the communicating passage, and means for covering
15 the inlet ports to the suction chamber in accordance with the adjustment of the valve and expanding elements.
7. The combination with a casing enclosing a suction chamber, and having inlet ports, an inner nozzle terminating in an opening within the chamber and axially concentric with the casing, and a diaphragm at the opposite end of the casing and pierced with a central orifice co-axial with the open-
20 ing within the nozzle, of a sleeve screwed to the casing and having a central valve seat
25 and forming a communicating passage

which admits the fluid pressure to the ori-
fice, a stuffing-box on the free end of the sleeve, a valve member having a central com-
30 municating passage extending longitudinally therein and its outer end arranged for screw connection with a hose, said valve having a screw connection with the casing and cooperating with the valve seat in closed 35 position to cut off the communicating passage to the orifice, and sliding through the stuffing-box, jet-spreading elements fixed to the end of the valve and projecting within the orifice, a ring mounted between the cas-
40 ing and sleeve and serving to support the jet-spreading elements, and expanding elements supported by the ring and extending between the jet-spreading elements, said jet-
45 spreading elements having longitudinal movement upon rotation of the valve, and said expanding elements being retained against longitudinal movement by the supporting ring, and said valve extending co-
50 axially with the suction casing.

In testimony whereof, I hereunto affix my signature.

JOHN GEORGE McGILPIN.
